(57) **CLAIM**

The ornamental design for a cup, as shown and described.

DESCRIPTION

FIG. 1 is a perspective view of a cup showing my new design;

FIG. 2 is a bottom view of the cup shown in FIG. 1;

FIG. 3 is a right side view of the cup shown in FIG. 1, the left side view being a mirror image thereof;

FIG. 4 is a perspective view of a second embodiment of the cup showing my new design;

FIG. 5 is a bottom view of the cup shown in FIG. 4; and, FIG. 6 is a right side view of the cup shown in FIG. 4, the left side view being a mirror image thereof.
